Application March 16, 1938, Serial No. 196,207

18 Claims. (Cl. 103—203)

My invention relates to the deep well pumping art, and more particularly to a method and apparatus for introducing a fluid to be pumped into a deep well pump.

5 Although my invention is susceptible of many uses, it is of particular utility in the oil industry and will be described in connection with a deep well pump adapted to pump oil from an oil well. It is to be understood, however, that this application of the invention is for the purpose of illustration only, and I do not intend to be limited thereby to the specific use described.

In the pumping of oil wells numerous types of pumps may be successfully utilized, as is well known in the art. Although the type of pump utilized forms no part of my present invention, I prefer to use my invention in conjunction with a fluid operated deep well pump of the type disclosed in my Letters Patent No. 2,081,220, issued 15 May 25, 1937, entitled "Liquid operated pump", which discloses a pump and motor unit adapted to be positioned in a well so as to pump fluid therefrom.

As is well known in the art, oil to be pumped from a well frequently has a substantial quantity of gas mixed therewith or in solution therein. The amount of gas in solution under equilibrium conditions depends on the temperature and pressure in the well and the analysis of both the oil and the gas. It is possible for the oil to be supersaturated, i. e., to have more gas in solution than the amount normally corresponding to equilibrium conditions. Agitation of a supersaturated solution causes the release of gas and tends to bring about equilibrium between the gas and the oil. Also when the pressure on the well fluid is decreased or the temperature increased, relatively large quantities of the gas therein are liberated and separate from the oil, forming a mixture therewith in the form of a foam or a suspension. Such gas produces a number of detrimental effects in the pumping, treating, conveying, and storing of the pumped fluid, and numerous devices have been devised and are common in 30 the art for separating such gas from the oil. Prior art devices for separating the gas from the oil prior to the pumping of the oil from the well have not produced satisfactory results, and it is a primary object of my invention to provide a 40 method and apparatus for separating at least a portion of the gas in the fluid to be pumped from a well therefrom prior to pumping such fluid from the well.

It is another object of my invention to provide 50 a method and apparatus for introducing into a

pump a liquid normally having a high degree of gas saturation, in which the degree of gas saturation is reduced before the liquid enters the pump.

Another object of my invention is to supply a method and apparatus for introducing into a 5 pump a liquid normally containing substantial quantities of gas, in which at least a portion of the gas is removed from the liquid, and the degree of gas saturation of the liquid is then reduced before the liquid enters the pump. I prefer to accomplish this by reducing the pressure on the liquid to remove at least a portion of the gas therefrom and then increasing the pressure thereon to reduce the degree of saturation of the liquid.

Another object of my invention is to provide a method and apparatus for use in connection with a deep well pump of the character described above for reducing to a minimum the tendency of the pump to cause the release of gas from 20 the pumped fluid and the resulting loss of pump capacity due to the space occupied by such gas.

Another object of my invention is to provide a method and apparatus for introducing fluid into a deep well pump in which the pressure of the 25 fluid to be pumped is reduced to casing pressure so as to liberate gas therefrom, and the fluid is then conveyed to the inlet of the pump under sufficient pressure so that said fluid is less than saturated with gas when it enters the pump.

Another object of the invention is to provide a method and apparatus for introducing well fluid into a deep well pump, in which gas pressure in the well is utilized to lift the fluid to a point adjacent the inlet of the pump, and the amount of 30 fluid so lifted is automatically controlled.

Still another object of my invention is to provide a method and apparatus for separating gas from a fluid, in which a mixture of the gas and fluid is conveyed into a chamber, the pressure in 40 the chamber is first reduced to a relatively low pressure to remove at least a portion of the gas from said fluid and is then subjected to a relatively high pressure to reduce the saturation of the gas in said fluid, and the fluid is then conveyed to a point of discharge under said high pressure.

A further object is to provide a method and apparatus for introducing fluid into a deep well pump in which the pump and apparatus may be 50 submerged to a point below the pumping fluid level in the well and in which the pumping fluid is subjected to the casing pressure to release gas therefrom into the casing and is then conveyed to the pump at the submergence pressure.

Another object is to provide a method and apparatus for controlling the flow of pumping fluid into the apparatus so that pumping fluid will not be permitted to rise in the casing and will put an excessive back pressure on the discharge of gas from the apparatus.

A further object is to provide a method and apparatus for separating gas from a liquid in which a mixture thereof initially at high pressure is carried through the cycle of reducing it to a lower pressure to release gas from the mixture, discharging the released gas at low pressure until substantial equilibrium is established, then subjecting the remaining liquid to the original high pressure so that it will be undersaturated at this pressure, and then discharging this stabilized liquid at the high pressure.

A further object is to provide a method and apparatus for introducing liquid into a well pump in which all the gas-liquid mixture from the well must pass through the apparatus and in which gas from the mixture is discharged into the casing at low pressure and the liquid is conveyed to the pump at the well pressure.

A further object of the invention is to provide an apparatus having a plurality of chambers adapted to receive a fluid having a gas mixed therewith, there being means for alternately subjecting said chambers to low and high pressures to liberate gas from said fluid and discharge said fluid from said chambers alternately, and having means adapted to be reciprocated as a result thereof.

Other objects and advantages will appear from the following specification and drawings, which are for the purpose of illustration only, and in which:

Fig. 1 is an elevational view, partly in section, of my invention installed in a well.

Fig. 2 is an enlarged vertical sectional view of the inlet means of my invention.

Fig. 3 is an enlarged cross-sectional view taken on the line 3-3 of Fig. 2.

Fig. 4 is another vertical sectional view of the structure shown in Fig. 2, taken on the line 4-4 of Fig. 3.

Fig. 5 is an enlarged cross-sectional view taken on the line 5-5 of Fig. 2.

Fig. 6 is an enlarged cross-sectional view taken on the line 6-6 of Fig. 2.

Fig. 7 is an enlarged cross-sectional view taken on the line 7-7 of Fig. 2.

Fig. 9 is an enlarged cross-sectional view taken on the line 9-9 of Fig. 2.

Fig. 10 is an enlarged cross-sectional view taken on the line 10-10 of Fig. 2.

Fig. 11 is a diagrammatic sectional view of the inlet means of my invention.

Referring to Fig. 1 of the drawings, I show a well casing 20 adapted to be positioned in a well as is well known in the art, having the usual perforated liner 21 in the lower end thereof. Adapted to be supported on the liner 21 is a packer means 22, comprising an upper ring clamp 23 having a tubular extension 24 on which rides a lower ring clamp 25 secured thereon by a suitable nut 26. The lower ring clamp 25 rests on the upper end of the liner 21, and a resilient packing member 27, made of rubber or other resilient material, is held between the lower and upper ring clamps. The upper face of the upper ring clamp 23 of the packer means 22 is provided with a concave seat 28 adapted to receive a convex face 29

formed on the lower end of an inlet means 30 of my invention. The lower end of the inlet means 30 is counterbored and internally threaded to receive a tubing member 31 extending downwardly through a central bore 32 in the tubular extension 24, the lower end of the tubing member being threaded to a perforated skeeter bill 33 extending downwardly into the liner, and being externally threaded to receive a nut 34. The lower end of the skeeter bill 33 is closed, as is common in the art. Threaded to the upper end of the inlet means 30 is a production tubing 35 extending upwardly therefrom to the surface of the ground, and a conical pump seat 36 is formed in the upper end of the inlet means to receive the lower tapered end of a pump unit 37, which has suitably connected thereto macaroni tubing 38 adapted to supply the pump unit with actuating fluid, the pump unit preferably being of the fluid operated type such as shown in my Letters Patent No. 2,081,220, issued May 25, 1937, although any suitable type of pump unit may be employed without departing from the spirit of my invention.

The inlet means 30, as shown in detail in Figs. 2 and 4, has an upper body 40 and a central body 41 preferably connected together by a threaded upper shell 42, and a lower body 43, preferably connected to the central body by means of a threaded lower shell 44, forming an upper chamber 45 and a lower chamber 46.

Formed in the lower body 43 is an offset inlet passage 47 communicating through a radial passage 48 with a central valve bore 49, also formed therein. Adapted to be reciprocated in the valve bore 49 and forming a sliding fluid-tight fit therewith is an inlet valve member 50 having upper and lower heads 51 and 52, respectively, connected by a stem 53. Connected to the upper head 51 by means of a suitable bolt 54 is a plate member 55 secured to the lower end of a flexible Sylphon bellows 56 which extends into a tubular cap 57 threaded into the lower body 43 concentric with the valve bore 49. Communicating with the interior of the valve bore 49 and the tubular cap 57 is a pressure passage 58 formed in the lower body 43, which also communicates with the exterior of the lower body, as shown in Fig. 2. Also communicating with the valve bore 49 is a radial opening 59 formed in the lower body 43 in the same plane as the radial passage 48, which opens into an intermediate passage 60 communicating with a sleeve bore 61 which receives the lower end of a lower sleeve 62 which makes a fluid-tight fit therewith, the upper end of the lower sleeve being similarly received in a lower counterbore 63 of an intermediate opening 64 formed in the central body 41. The upper end of the intermediate opening 64 has an upper counterbore 65 which receives the lower end of an upper sleeve 66, the upper end thereof being received in a bore 67 formed in the upper body 40. Upper inlet orifices 68 are provided in the upper sleeve 66 communicating with the upper chamber 45, and lower inlet orifices 69 are provided in the lower sleeve 62 communicating with the lower chamber 46. The inlet passage 47, the valve member 50, the Sylphon bellows 56 connected therewith, and the associated passages form a flow governor for controlling the flow of well fluid into the inlet means 30 from the well through the tubing member 31, as will be described hereinafter.

The upper body 40 is provided with a cylindrical bore 70 which receives an upper piston 71

comprised of a lower head 72 and an upper head 73 joined by a stem 74 to provide an annular gas discharge chamber 75 adapted to communicate with a pair of upper gas discharge openings 76 which communicate with the exterior of the upper body 40, and which communicates through an upper exhaust passage 76a with the upper chamber 45. Threadedly received in the lower end of the cylindrical bore 70 is a plug 77 having a vertical orifice 78 communicating between the upper chamber 45 and the lower face of the piston 71 to permit fluid pressure in the upper chamber to act on the lower face of the piston 71, and a deflected passage 79 is likewise provided in the upper body 40 communicating between the upper chamber and the upper face of the piston to permit fluid pressure in the upper chamber to act on the upper face of the piston to maintain balanced fluid pressures on opposite ends of the piston.

The central body 41 is likewise provided with a cylindrical bore 80 having a lower piston 81 therein comprised of a lower head 82 and an upper head 83 connected by a stem 84 to provide an annular gas discharge chamber 885 adapted to communicate with a pair of lower gas discharge openings 86, similar to the upper discharge openings 76, which communicate with the exterior of the central body, and which communicates through a lower exhaust passage 86a with the lower chamber 46. Threadedly received in the upper end of the cylindrical bore 80 is a lock plug 87 having a vertical orifice 88 communicating between the upper chamber 45 and the upper face of the piston 81 to permit fluid pressure in the upper chamber to act on the upper face of the piston, and a deflected passage 89 is likewise provided in the central body 41 communicating between the upper chamber 45 and the lower face of the piston to permit fluid pressure in the upper chamber to act on the lower face of the piston to maintain balanced fluid pressures on opposite ends of the piston 81.

The upper and lower pistons 71 and 81 are preferably rigidly connected together by a piston rod 90 so that the pistons and rod move in unison, the piston rod passing through a suitable journaling opening formed in the plug 77. Secured on the piston rod 90 is a hollow float 91 positioned to move in the upper chamber 45, the float being adapted to move in response to changes in the fluid level therein, as will be more fully described hereinafter. Also secured on the piston rod 90 is a locking sleeve 92 having V-shaped annular grooves 93 and 94 in the exterior surface thereof, as shown in Fig. 4, which are adapted to be alternately engaged by a ball locking member 95 carried in a radial passage 96 formed in the locking plug 87, the ball member being forcibly held in engagement with the locking sleeve by a spring 97 held in place by a screw plug 98, as shown in Fig. 2.

As shown in Fig. 2, the central body 41 is provided with check valve means in the form of an offset bore 100 having a concentric counterbore 101 receiving a tubular valve seat member 102 in which a ball valve 103 is adapted to seat, the ball valve normally being held in seated position by a compression spring 104 retained in the seat member by the lower end of a discharge pipe 105 journalled therein at one end and journalled at its other end in a discharge opening 106 formed in the upper body 40. The discharge opening 106 communicates at its upper end with the inlet 107 of the pump unit 37. The lower end of the off-

set bore 100 communicates with a central discharge passage 108 formed in the central body 41 and communicating with the lower end of the upper chamber 45.

As shown in Fig. 4, the lower body 43 is provided with check valve means in the form of an offset bore 110 having a concentric counterbore 111 receiving a tubular valve seat member 112 in which a ball valve 113 is adapted to seat, the ball member normally being held in seated position by a compression spring 114 retained in the seat member by the lower end of a discharge pipe 115 journalled therein at one end and journalled at its other end in a vertical opening 116 formed in the central body 41. A connecting pipe 117 is received in the upper end of the opening 116 and connects it to the discharge pipe 105, as best shown in Figs. 2 and 7. The lower end of the offset bore 110 communicates through a lower discharge passage 118 formed in the lower body 43 with the lower end of the lower chamber 46, as best shown in Fig. 2.

In installing the device in a well, the liner 21 is first lowered into the casing 20 in the usual manner, the liner being of a length considerably less than the height to which well fluid would normally rise in the well, as represented, for example, by the line A—A shown in Fig. 1. To the lower end of the production tubing 35 is connected the inlet means 30 and the packer means 22 which are then lowered into the casing 20 as a unit by means of the production tubing until the lower clamp ring 25 of the packer means engages and is supported on the upper end of the liner 21. The weight of the production tubing 38 and the inlet means 30 bears on the upper clamp ring 23 of the packer means 22, causing the upper clamp to move down relative to the lower clamp ring 25 to compress and expand the packing member 27 into sealing relation with the casing 20. The convex face 29 and concave seat 28 insure that a fluid-tight joint is made between the packer means 22 and the inlet means 30 even though the packer means and inlet means are not perfectly axially aligned. Preferably before the inlet means 30 is lowered into the casing 20, the flexible Sylphon bellows 56 is filled with fluid under pressure, such as air, by any suitable means, the pressure used therein being determined by operating conditions in the well. I have found that 100 pounds per square inch is a common working pressure for the flexible Sylphon bellows 56, but it will be understood that this pressure may be increased or decreased to conform to flow conditions in a particular well.

After the packer means 22 is positioned in the casing 20, as shown in Fig. 1, the pump unit 37 may then be assembled and connected to the macaroni tubing 38 by means of which it is lowered through the production tubing 35 until the lower tapered end thereof seats in the conical seat 36 to form a fluid-tight joint therewith. Although I have disclosed a system in which for convenience the pump unit 37 is sufficiently small in diameter to be lowered into operating position through the production tubing 35, it will be apparent that a pump of any suitable size and design may be utilized without departing from the invention.

The operation of the invention is as follows: Oil from the well formation flows through the perforations in the liner 21 and the skeeter bill 33, and is forced upwardly through the tubing member 31 by the fluid pressure on the well fluid below the packer means 22. As is well known in

- the oil industry, formation pressure in an oil well is ordinarily sufficient to lift the well fluid through considerable distances, which fact has been widely utilized in the art in various well known types of oil lifts. The course of the well fluid is indicated by arrows in Fig. 2, the fluid flowing upwardly from the tubing member 31, through the inlet passage 47, the radial passage 48, around the stem 53 of the valve member 50, through the radial opening 59, through the lower sleeve 62, the intermediate opening 64, the upper sleeve 66, and through the upper and lower inlet orifices 68 and 69 into the upper and lower chambers 45 and 46, respectively. The inlet passage 47, the valve member 50 and associated openings, the lower sleeve 62, the intermediate opening 64, and the upper sleeve 66 thus form an entrance passage 120 for fluid flowing from the well.
- It will be noted that when the flexible Sylphon bellows 56 is assembled in the tubular cap 57 in the inlet means 30, as shown in Figs. 2 and 4, operating pressure within the bellows will cause it to expand, moving the plate member 55 and inlet valve member 50 connected thereto downwardly substantially to the bottom of the valve bore 49 to the position shown. When in this position, the stem 53 and the space between the upper and lower heads 51 and 52 is substantially upper and lower heads 51 and 52 is substantially 25 aligned opposite the radial passage 48 and radial opening 59, so that open communication is provided between the inlet passage 47 and the intermediate passage 60 through the valve bore 49 around the stem. Any rise of fluid pressure 30 in the space 125 between the well casing 20 and the inlet means 30 is communicated through the pressure passage 58 to the valve bore 49 above the valve member 50 and to the interior of the tubular cap 57 to act against the exterior of the 35 Sylphon bellows 56 and the bottom of the plate 40 member 55 to tend to compress the bellows. If this fluid pressure rises above the operating pressure within the Sylphon bellows 56, as described hereinabove, the Sylphon bellows will contract 45 as a result of the action thereof to raise the valve member 50. As the valve member 50 rises, the lower head 52 restricts the communication between the radial passage 48 and the radial opening 59 to decrease the flow of well fluid 50 therethrough. A sufficient rise in fluid pressure 55 in the space 125 will cause the Sylphon bellows 56 to contract to such an extent that the lower head 52 of the valve member 50 will completely close the communication between the radial passage 48 and the radial opening 59, to prevent any well fluid from flowing into the inlet means 30 from the tubing member 31 until the fluid pressure in the space 125 decreases to such an extent that the operating pressure within the 60 Sylphon bellows 56 can operate to expand the bellows to force the valve member downwardly until the lower head clears the radial passage and opening, at which time the flow of well fluid will be resumed from the tubing member into the inlet means. The amount of opening of the valve member 50 will thus be understood to be inversely proportional to the difference in fluid pressure in the space 125 and the Sylphon bellows 56, the amount of opening automatically increasing or decreasing with such change in pressure difference within the limits of the device, thus providing means for automatically controlling the volume of flow of well fluid into the inlet means in accordance with the fluid pressure in the space 125. As will be pointed out hereinafter, it is desirable to discharge gas at low pressure into the space 125, and, since both the inlet means 30 and the pump unit 31 are preferably submerged in fluid to a level such as represented by the level A—A in Fig. 1, it is an important object to maintain the level of the fluid in the space 125 above the packer means 22 below a predetermined maximum so as to prevent the fluid pressure on the gas discharge openings 76 and 86 from exceeding that at which gas is to be discharged therefrom. Thus, it will be understood that the head of fluid in the space 125 above the packer means 22 will automatically control the flow of well fluid into the inlet means. If this head of fluid rises above its predetermined maximum, the flow of well fluid into the inlet means 30 will be restricted or stopped, and the pump unit 31 will then operate to reduce the head by pumping fluid from the space 125 through the gas discharge openings 76 or 86, one of which is open to the space 125 at all times, until the head falls below a predetermined minimum, at which time the flow of well fluid into the inlet means is resumed. Although under some well conditions my inlet means 30 will operate satisfactorily without the pressure controlled mechanism for controlling the flow of well fluid into the inlet means, I prefer to incorporate this mechanism to provide universal application of the invention. It will be understood, however, that I do not intend to be limited to a device incorporating such a mechanism as described.
- The fluid pressure in the space 125 is also communicated to the lower end of the valve bore 49 below the valve member 50 through a valve balance passage 58a, so that the valve member will be subjected to equal fluid pressures above and below it to substantially balance the valve member.
- The well fluid flowing from the well into the inlet means 30 normally has a substantial quantity of gas mixed therewith or in solution therein so as to have a high degree of gas saturation, as described hereinabove, and, as stated, this well fluid flows from the entrance passage 120 through the upper and lower inlet orifices 68 and 69 into the upper and lower chambers 45 and 46, respectively. When the parts are in the position shown in Figs. 2, 3, and 4, the upper chamber 45 is in open communication with the space 125 in the well casing 20 through the upper exhaust passage 76a, the gas discharge chamber 75, and the gas discharge openings 76, and consequently the upper chamber is at casing pressure, which may be at or about atmospheric pressure depending on the head of fluid above the openings 76 in the space 125. Well fluid flowing into the upper chamber 45 from the entrance passage 120 is under considerable pressure, due to the natural formation pressure of the well, but when it enters the upper chamber the pressure thereon is reduced to or about casing pressure, and gas is liberated, the liberated gas flowing upwardly in the upper chamber 45, through the exhaust passage 76a, the exhaust chamber 75, and the gas discharge openings 76, into the space 125 of the well casing 20 exterior to the inlet means 30, from whence the gas may flow upwardly through the casing to a suitable point of discharge or storage (not shown). In the meantime, clean oil from which the gas has been released commences to fill the upper chamber 45, the level thereof rising therein.
- As the upper chamber 45 is filling with oil, well 75

fluid will also flow into the lower chamber 46, tending to fill it up. As shown in Figs. 2 and 4, however, the lower piston 81 is in lowered position in which the upper head 83 thereof closes the lower gas discharge openings 86, and consequently the pressure in the lower chamber quickly rises so that very little gas is released from the oil flowing thereto. Although the pressure in the lower chamber 46 tends to rise, the compression spring 114 maintains the ball valve member 113 closed to prevent a premature discharge of oil from the lower chamber.

When the oil level in the upper chamber 45 contacts the float 91, it tends to raise the float 15 due to the buoyancy of the latter. When the upward pressure on the float 91 reaches a predetermined value, the float, piston rod 90, and locking sleeve 92 will move upwardly, forcing the ball locking member 95 outwardly in the radial passage 96 against the action of the spring 97. The locking sleeve 92 and associated elements will move upwardly until the lower annular groove 94 thereof moves into alignment with the radial passage 96, at which time the ball locking member 95 enters the lower annular groove to lock the locking sleeve, the float 91, the piston rod 90, and the upper and lower pistons 71 and 81 in raised position. The locking sleeve 92 and ball locking member 95 thus comprise a locking means 20 for locking the piston assembly comprised of the piston rod 90, float 91, and upper and lower pistons 71 and 81, in either an upper or lower position, and preventing the rod from creeping between such positions. The elements are preferably so proportioned that the piston rod will snap from one position to another, which is another object of the invention.

When the piston rod 90 moves to its raised position, as described, the lower head 72 of the upper piston 71 closes the gas discharge openings 76 so that communication between the upper chamber 45 and the casing 20 is cut off, and, accordingly, the fluid pressure in the upper chamber commences to rise. With the piston rod 90 in such raised position, the lower piston 81 will be raised sufficiently so that the annular discharge chamber 85 registers with the lower gas discharge openings 86 to open communication between the upper end of the lower chamber 46 and the casing 20, through the exhaust passage 86a, the annular discharge chamber, and the lower discharge openings, and, accordingly, the free gas in the lower chamber exhausts into the casing, and the fluid in the lower chamber is reduced to casing pressure. When this occurs, well fluid flows into the lower chamber 46 through the lower inlet passageway 64 from the entrance passage 120, and, being immediately reduced to casing pressure, gas is liberated therefrom and the lower chamber starts to fill with oil, as described above in connection with the operation of the upper chamber 45.

Fluid pressure in the upper chamber 45 quickly builds up to a pressure sufficient to cause the ball valve member 103 to move away from its seat against the action of the compression spring 104, and this pressure then causes oil to flow from the upper chamber through the central discharge passage 108, the offset bore 100, the valve seat member 102, the discharge pipe 105, and the discharge opening 106 to the inlet 107 of the pump unit 37, from whence it may be pumped to the surface of the ground as is customary in the art.

As oil flows from the upper chamber 45 through the central discharge passage 108, the level thereof

drops in the upper chamber until it is adjacent the lower end of the float 91, at which time the weight of the piston assembly overcomes the locking action of the ball locking member 95 in the lower annular groove 94, causing the ball member to move outwardly to release the locking sleeve 92 to permit the locking sleeve, the piston rod 90, and connected upper and lower pistons 71 and 81 to move downwardly until the ball locking member moves into the upper annular groove 109, at which time the piston rod assembly is locked in its lower position.

While the piston rod assembly is in its upper position, as described, oil flows from the upper chamber 45 under a relatively high pressure to the inlet 107 of the pump unit 37, and during such period the lower chamber 46 is filling with oil and discharging gas into the casing 20. As soon as the piston rod assembly moves downwardly into its lower position, as described, the action of the upper and lower chambers is reversed, and the upper chamber 45 refills with oil and discharges gas into the casing 20 while the lower chamber 46 discharges oil to the inlet 107 of the pump unit 37. It will be apparent that the lower chamber 46 discharges oil to the pump unit 37 similarly to the upper chamber, the pressure in the lower chamber displacing the ball valve 113 and causing oil to flow through the lower discharge passage 108, the offset bore 110, the valve seat member 112, the discharge pipe 115, the vertical opening 116, and the connecting pipe 117 into the discharge pipe 105 from whence it is conveyed to the pump inlet 107 through the discharge opening 106. The device is so designed that a substantially continuous flow of oil under pressure is supplied to the inlet 107 of the pump unit 37. By maintaining a relatively high pressure on the oil flowing to the pump unit 37, any gas remaining in the oil is compressed so that the oil flowing to the pump unit is at all times less than saturated with gas. This prevents the release of gas in the pump unit 37 during pumping, and insures that the pump is entirely filled with oil and is free from gas bubbles, which maintains a high pumping efficiency.

It will also be apparent that during normal operation of my device the piston rod 90 reciprocates in accordance with the operation of the device, and this is another object of my invention.

The oil flowing into the inlet means 30 from the well may be under any one of three possible conditions; i. e., the oil may be supersaturated with gas, it may be saturated with gas, or it may be less than saturated with gas, the reference equilibrium conditions being the pressure and temperature existing in the well below the packer means 22. The oil, under any of these conditions, may also have free gas mixed therewith in the form of a foam or suspension of gas bubbles in the oil.

The absolute amount of gas in solution at constant temperature depends on the pressure and the per cent of saturation at this pressure, which may vary from zero to more than 100%. A liquid which is less than saturated at high pressure may become supersaturated at low pressure and release gas. Conversely, a liquid which is supersaturated at low pressure will be saturated at a certain higher pressure and will have only a small percentage saturation at a relatively very high pressure. Both undersaturated and oversaturated solutions are unstable, but oversaturated solutions can be reduced to approximate saturation.

tion more readily than undersaturated solutions can be saturated because when gas is released, a mechanical gravity separation of gas bubbles takes place, and hence the gas can rise rapidly through the liquid. However, when gas is going into solution, it must diffuse into the liquid unless artificially agitated, and diffusion is a very slow process.

If the oil is supersaturated with gas as it flows 10 into the inlet means 30, it will have more gas dissolved therein than normal under equilibrium conditions at the particular temperature and pressure existing. Flow of this oil through the inlet means 30 into the entrance passage 120 15 causes considerable agitation and will release from the oil at least a portion of the gas causing the supersaturated condition. When the oil flows into either the upper or lower chambers 45 or 46 which are at reduced pressure (casing pressure), a large amount of gas is released from the 20 oil. Since the casing pressure in either the upper or lower chamber 45 or 46 is much lower than that of the oil entering it, the amount of gas which will remain in solution in the oil under 25 equilibrium conditions at the reduced pressure is small compared with the amount of gas originally in the oil. Consequently, the degree of gas saturation of the oil rises far above the saturation point, for equilibrium at the reduced pressure, and the excess of this temporarily supersaturated solution quickly flashes out of solution, leaving oil in the chamber which is substantially saturated with gas at the reduced pressure. Thus, it will be appreciated that the oil flowing 30 into the inlet means 30 from the well, which is supersaturated with gas at high pressure, is further supersaturated by reducing the pressure, the excess gas corresponding to the supersaturation then flashing out of solution to form a substantially 35 saturated solution of oil and gas in the chamber at a low pressure.

If the oil is substantially saturated with gas as it flows into the inlet means 30, the reduction in pressure in either of the chambers 45 or 46 into 45 which it flows causes a reduction in the stable amount of gas corresponding to the saturation point at the reduced pressure, which in turn renders the oil supersaturated with relation to equilibrium conditions in the chamber, and the 50 excess gas separates from the oil, leaving oil substantially saturated with gas in the chamber.

If the oil is less than saturated with gas as it flows into the inlet means 30, the reduction in pressure thereon on flowing into either of the chambers 45 or 46 will increase the degree of saturation of the oil. If more gas is in solution than would be normally possible for an equilibrium condition in the chamber, as the pressure is lowered the oil will first become saturated and will then become supersaturated, and the excess gas will then flash out, leaving a saturated oil in the chamber. If, however, less gas is in solution than would normally be possible for an equilibrium condition in the chamber, then the degree of saturation will rise but will not exceed the saturation point, and consequently no excess gas will be available to separate from the oil.

It will be appreciated that any free gas in the 70 oil in the chambers 45 or 46, whether released from the oil by reason of the change in pressure conditions as described above or merely mixed therewith, will separate from the oil by gravity separation under the low pressure conditions existing in the chambers, and, consequently, such

gravity separation of the gas from the oil is another important feature of the invention.

Since, from the foregoing explanation, the oil in either of the chambers 45 or 46 will never be substantially more than saturated with gas at the 5 conditions of temperature and pressure existing in the chambers which corresponds to the casing pressure, which is materially less than the well pressure, and since well pressure is put on this oil to cause it to flow to the pump unit 37, it will 10 be apparent upon the increase of pressure thereof, that the clean oil flowing to the pump unit will always be less than saturated, which is an important purpose of the invention, since it is desirable to always supply oil to the pump which is 15 less than saturated so as to prevent the liberation of free gas in the pump unit during the operation thereof.

Although I have herein shown and described my invention in simple and practical form, it 20 will be recognized that certain parts or elements thereof are representative of other parts, elements, or mechanisms which may be used in substantially the same manner to accomplish substantially the same results; therefore, it is to be 25 understood that the invention is not to be limited to the details of structure or application disclosed herein but is to be accorded the full scope of the following claims.

I claim as my invention:

1. In a liquid treating device, the combination of: a first chamber; a second chamber; means for introducing a liquid containing gas into said chambers; means for removing gas from said liquid alternately in said chambers; means for reducing the degree of saturation of said liquid to a value at which said liquid is less than saturated with said gas alternately in said chambers; and means for alternately conveying said liquid from said chambers. 30

2. In a liquid treating device, the combination of: a first chamber; a second chamber; means for introducing a liquid normally containing gas into said chambers; means for increasing the degree of saturation of said liquid alternately in 35 said chambers so as to liberate gas from said liquid; means for alternately conveying said liquid from said chambers; and means for automatically governing the amount of said liquid introduced into said chambers. 40

3. In a liquid treating device, the combination of: a first chamber; a second chamber; means for introducing liquid into said chambers; valve means for reducing the pressure in said first chamber and permitting the exhaust of gas therefrom; port means for reducing the pressure in said second chamber and permitting the exhaust of gas therefrom; valve closing means for closing said valve means to raise the pressure in said first chamber to cause liquid to discharge therefrom; and port closing means for closing said port means to raise the pressure in said second chamber to cause liquid to discharge therefrom, said valve closing means and said port closing means operating so that said chambers discharge 55 fluid alternately. 60

4. In a liquid treating device, the combination of: a first chamber; check valve means associated with said first chamber so as to permit a discharge of liquid from said chamber; a second 70 chamber; discharge valve means associated with said second chamber so as to permit a discharge of liquid from said chamber; means for introducing liquid to be treated into said chambers; a first valve means movable between open and 75

closed positions, said valve means when in open position reducing the pressure in said first chamber and permitting the exhaust of gas therefrom and permitting said chamber to fill with liquid, said valve means when in closed position closing said first chamber to permit fluid pressure to build up therein to force said liquid from said first chamber through said check valve means; second valve means movable between open and closed positions, said valve when in open position reducing the pressure in said second chamber and permitting the exhaust of gas therefrom and permitting said chamber to fill with liquid, said valve means when in closed position closing said second chamber to permit fluid pressure to build up therein to force said liquid from said second chamber through said discharge valve means; and means for causing said first valve means to open and said second valve means to close simultaneously, and for causing said first valve means to close and said second valve means to open simultaneously.

5. In a deep well pumping device, the combination of: packer means adapted to be positioned in a well below the normal level of fluid in said well to form a fluid-tight seal with the casing of said well; pumping means adapted to be positioned in said well, said pumping means having a pump inlet; and inlet means communicating between said well below said packer and said pump inlet for supplying well fluid from said well to said pump inlet, all of the flow of well fluid from said well passing through said inlet means, said inlet means being adapted to separate gas from said well fluid and to convey said well fluid under pressure to said pump inlet.

6. In a deep well pumping device, the combination of: packer means adapted to be positioned in a well below the normal level of fluid in said well to form a fluid-tight seal with the casing of said well; pumping means adapted to be positioned in said well, said pumping means having a pump inlet; inlet means communicating between said well below said packer and said pump inlet for supplying well fluid from said well to said pump inlet, all of the flow of well fluid from said well passing through said inlet means, said inlet means being adapted to separate gas from said well fluid and to convey said well fluid under pressure to said pump inlet; and means for controlling the rate of flow of well fluid through said inlet means.

7. In a deep well pumping device, the combination of: packer means adapted to be positioned in a well below the level to which fluid would normally rise in said well to form a fluid-tight seal with the casing of said well; pumping means having a pump inlet, said pumping means being adapted to be positioned in said well so that the inlet thereof is below said level; and inlet means communicating between said well below said packer and said pump inlet for supplying well fluid from said well to said pump inlet, all of the flow of well fluid from said well passing through said inlet means, said inlet means being adapted to separate gas from said well fluid and to convey said well fluid under pressure to said pump inlet.

8. In a deep well pumping device, the combination of: packer means adapted to be positioned in a well below the level to which liquid would normally rise in said well to form a fluid-tight seal with the casing of said well; pumping means adapted to be positioned in said well, said pumping means having a pump inlet; inlet means adapted to be positioned in said well above said

5. packer means and below said pumping means, said inlet means having an inlet member extending downwardly through said packer means so as to permit well fluid to flow from said well below said packer means into said inlet means, said inlet means having a discharge passage communicating with said pump inlet so as to supply said well fluid to said pumping means, said inlet means being adapted to separate gas from said well fluid and to convey said well fluid under 10 pressure through said discharge passage to said pump inlet.

9. In a device of the character described, the combination of: a body member having a discharge opening; walls defining a first chamber in 15 said body member; walls defining a second chamber in said body member; means for introducing fluid into said chambers; walls forming a first exhaust passage communicating between said first chamber and the exterior of said body member; 20 walls forming a second exhaust passage communicating between said second chamber and the exterior of said body member; valve means adapted to cooperate with said exhaust passages to open and close said passages; walls forming a 25 first discharge passage communicating between said first chamber and said discharge opening; walls forming a second discharge passage communicating between said second chamber and said discharge opening; and means for actuating 30 said valve means to open and close said exhaust passages.

10. In a device of the character described, the combination of: a body member having a discharge opening; walls defining a first chamber in 35 said body member; walls defining a second chamber in said body member; means for introducing fluid into said chambers; means for controlling the rate of flow of said fluid into said chambers; walls forming a first exhaust passage communicating between said first chamber and the exterior of said body member; 40 walls forming a second exhaust passage communicating between said second chamber and the exterior of said body member; valve means adapted to cooperate with said exhaust passages to open and close said passages; walls forming a first discharge passage communicating between said first chamber and said discharge opening; walls forming a second discharge passage communicating between said second chamber and said discharge opening; and means for actuating 45 said valve means to open and close said exhaust passages.

11. In a device of the character described, the combination of: a body member having a discharge opening; walls defining a first chamber in 55 said body member; walls defining a second chamber in said body member; means for introducing fluid into said chambers; walls forming a first exhaust passage communicating between said first chamber and the exterior of said body member; 60 walls forming a second exhaust passage communicating between said second chamber and the exterior of said body member; valve means adapted to cooperate with said exhaust passages to open and close said passages; walls forming a first discharge passage communicating between said first chamber and said discharge opening; walls forming a second discharge passage communicating between said second chamber and said discharge opening; and means operable in 65 response to a predetermined change in the level of fluid in one of said chambers for actuating said valve means to open and close said exhaust passages.

12. In a deep well pumping device, the combination of: packer means adapted to be positioned in a well below the normal level of fluid in said well to form a fluid-tight seal with the wall of said well; pumping means adapted to be positioned in said well, said pumping means having a pump inlet; and inlet means communicating between said well below said packer means and said pump inlet for supplying well fluid from said well to said pump inlet, said inlet means being adapted to separate gas from said well fluid and to convey said well fluid under pressure to said pump inlet.
13. In a device for introducing well fluid into a deep well pump, the combination of: packer means adapted to be positioned in a well below the normal level of fluid in said well to form a fluid-tight seal with the casing of said well, said packer means forming a fluid space thereabove; pumping means adapted to be positioned in said well, said pumping means having a pump inlet; inlet means communicating between said well below said packer means and said pump inlet for supplying well fluid from said well to said pump inlet, said inlet means being adapted to separate gas from said well fluid and to convey said well fluid under pressure to said pump inlet; and control means for adjustably regulating the flow of well fluid through said inlet means, said control means operating in response to fluid pressure in said fluid space.
14. In a device for introducing well fluid into a deep well pump, the combination of: packer means adapted to be positioned in a well below the normal level of fluid in said well to form a fluid-tight seal with the casing of said well; pumping means adapted to be positioned in said well, said pumping means having a pump inlet; and inlet means communicating between said well below said packer means and said pumping inlet for supplying well fluid from said well to said pump inlet, said inlet means including means for reducing the pressure on said well fluid to substantially atmospheric pressure to separate gas from said well fluid and including means for conveying said well fluid under pressure to said pump inlet.
15. In a device for introducing well fluid into a deep well pump, the combination of: packer means adapted to be positioned in a well below the normal level of fluid in said well to form a fluid-tight seal with the casing of said well; pumping means adapted to be positioned in said well, said pumping means having a pump inlet; and inlet means communicating between said well below said packer means and said pump inlet for supplying well fluid from said well to said pump inlet, said inlet means including means for reducing the pressure of said well fluid to substantially atmospheric pressure to separate gas from said fluid, means for increasing the pressure of said well fluid above said atmospheric pressure, and means for conveying said well fluid to said pump at said increased pressure so that said well fluid is less than saturated with gas as it enters said pump.
16. In a device for introducing well fluid into a deep well pump, the combination of: packer means adapted to be positioned in a well below the normal level of fluid in said well to form a fluid-tight seal with the casing of said well; pumping means adapted to be positioned in said well, said pumping means having a pump inlet;

and inlet means communicating between said well below said packer means and said pump inlet for supplying well fluid from said well to said pump inlet, said inlet means including means for increasing the degree of gas saturation of said well fluid so as to liberate gas from said liquid, means for reducing the degree of gas saturation of said well fluid materially below the saturation point of said well fluid, and means for conveying said well fluid to said pump inlet so that said well fluid will be less than saturated with gas as it enters said pumping means.

17. In a device of the character described, the combination of: walls forming a chamber; an inlet passage communicating between said chamber and a source of liquid under relatively high pressure; discharge valve means associated with and communicating with said chamber, said discharge valve means being adapted to prevent a flow of liquid therethrough when the fluid pressure in said chamber is below a predetermined value and adapted to permit a flow of liquid therethrough when the pressure in said chamber is above said predetermined value; walls forming an exhaust passage communicating between said chamber and a point of exhaust; valve means cooperating with said exhaust passage, said valve means when open reducing the fluid pressure in said chamber below said predetermined value to permit liquid to flow into said chamber from said inlet passage at reduced pressure to liberate gas therefrom, said gas discharging through said exhaust passage; and means for closing said valve means so that said liquid flows into said chamber from said inlet passage at increased pressure to raise the fluid pressure in said chamber above said predetermined value, causing liquid to flow from said chamber under pressure through said discharge valve means.

18. In a device of the character described, the combination of: walls forming a chamber; an inlet passage communicating between said chamber and a source of liquid under relatively high pressure; discharge valve means associated with and communicating with said chamber, said discharge valve means being adapted to prevent a flow of liquid therethrough when the fluid pressure in said chamber is below a predetermined value and adapted to permit a flow of liquid therethrough when the pressure in said chamber is above said predetermined value; walls forming an exhaust passage communicating between said chamber and a point of exhaust; valve means cooperating with said exhaust passage, said valve means when open reducing the fluid pressure in said chamber below said predetermined value to permit liquid to flow into said chamber from said inlet passage at reduced pressure to liberate gas therefrom, said gas discharging through said exhaust passage; means for closing said valve means so that said liquid flows into said chamber from said inlet passage at increased pressure to raise the fluid pressure in said chamber above said predetermined value, causing liquid to flow from said chamber under pressure through said discharge valve means; and a piston rod adapted to be reciprocated in response to the rise and fall of the liquid level in said chamber.

CLARENCE J. COBERLY.

CERTIFICATE OF CORRECTION.

Patent No. 2,179,482.

November 14, 1939.

CLARENCE J. COBERLY.

It is hereby certified that error appears in the printed specification of the above numbered patent requiring correction as follows: Page 3, first column, line 25, for "chamber 885" read chamber 85; page 7, first column, line 70, claim 8, for the word "liquid" read fluid; page 8, first column, line 40, claim 14, for "pumping" read pump; and that the said Letters Patent should be read with this correction therein that the same may conform to the record of the case in the Patent Office.

Signed and sealed this 26th day of December, A. D. 1939.

(Seal)

Henry Van Arsdale,
Acting Commissioner of Patents.
